UNITED STATES PATENT OFFICE.

HERMAN G. C. SCHWARZE, OF DETROIT, MICHIGAN, ASSIGNOR TO CADILLAC MOTOR CAR COMPANY, OF DETROIT, MICHIGAN, A CORPORATION OF MICHIGAN.

HYDROCARBON-MOTOR.

1,286,803.

Specification of Letters Patent.

Patented Dec. 3, 1918.

Application filed November 20, 1915. Serial No. 62,493.

To all whom it may concern:

Be it known that I, HERMAN G. C. SCHWARZE, a citizen of the United States, and resident of Detroit, Wayne county, 5 State of Michigan, have invented certain new and useful Improvements in Hydrocarbon-Motors, of which the following is a specification.

One of the most difficult problems, arising 10 in connection with the operation of high speed multicylinder internal combustion engines, has been to provide an ignition system which will adequately and efficiently ignite the explosive charge at the proper intervals. This problem will be appreciated 15 when it is considered that an eight cylinder, four cycle motor, running at a speed of 3,000 revolutions per minute requires 200 sparks per second. When it is appreciated that 20 these sparks are, in many instances, produced from a single induction coil, one realizes the importance of the problem which 25 the extraordinary time factor involves, in properly energizing the induction coil; that is, it has been found very difficult to energize and deenergize the induction coil in the brief period of time in which this must be done.

One way of overcoming the difficulty, 30 heretofore, has been to accelerate the action of the induction coil by an increase of the flow of current, by raising the electromotive force or lowering the resistance in the primary circuit. Of course, when this is done, 35 the increase of current causes excessive sparking between the make and break contacts at low speeds, tending to oxidize the contacts, and thus increasing the resistance between them, and necessitating their replacement or repair at short intervals.

Another method which has been proposed 40 to overcome some of these difficulties, is to provide two sets of contacts each of which is adapted to close the circuit alternately, 45 and, of course, if one set of contacts wears or burns away, thus destroying the firing balance of the motor, frequent replacement or adjustment of the contacts is necessary. With such an arrangement, it will be seen 50 that if the timing of half of the cylinders is dependent on one set of contacts, and the other half on another set of contacts, after wear has taken place between one set of contacts, one half of the cylinders may be 55 late in firing so as to heat the motor, and the

other half of the cylinders may be early in firing, so as to cause premature ignition and spark knock.

Another method, which has been proposed to overcome these difficulties, is to enlarge 60 the contact area. This has been found undesirable because of the inertia of these parts at high speeds.

Another difficulty heretofore experienced in using a single set of contacts has been, 65 that due to the eccentricity of the operating cam, and to looseness of the bearings, in which the timer shaft is mounted, these errors are very pronounced in destroying the firing balance of the motor.

Another difficulty in connection with the use of a single set of contacts is that at high 70 speeds the contacts tend to chatter when closing, thus causing a tendency to discharge the condenser, which causes an undesirable 75 arcing between the contacts.

Therefore, to overcome these and other serious objections to present ignition systems, there has been provided a timer with 80 two sets of contacts, which may be in parallel, both sets being adapted to open and close the primary circuit simultaneously and independently, each set carrying half the current, and thereby reducing the sparking effect to a minimum. With two sets of 85 contacts provided, as will be hereinafter described, the arcing, which has heretofore been caused by a chatter of the contacts at high speeds has been reduced to a minimum, as the two sets of contacts do not chatter in 90 synchronism. This may be explained as follows: Assuming that the adjustment of two sets of contacts is not accurate, and as a result of faulty adjustment one set opens late, all arcing takes place on this set, caus- 95 ing the points to burn or waste away until this set opens in synchronism with the opposite set; therefore, they automatically tend to open and close in synchronism.

With this arrangement, it is made possible 100 to operate the motor at much higher speed without serious sparking of contacts than has heretofore been accomplished.

Another great advantage in the use of this invention, is that if one set of contacts is 105 disabled causing it to be inoperative, there is still provided another set which will operate the motor until facilities are given for replacement.

It will also appear that with two sets of 110

contacts arranged 180 degrees apart, and adapted to be operated from cam faces mounted on a single shaft, the disturbance of the firing balance of the motor, which is usually caused by eccentricity of cams and looseness of bearings on which they are mounted, is reduced to a minimum, so that the various cylinders on alternate revolutions fire in substantial synchronism.

10 These and other objects will appear from the following description taken in connection with the accompanying drawings showing a preferred form of this invention, and in which:

15 Figure 1 is a diagrammatic view illustrating the invention, as applied to an ignition system, as used with an internal combustion engine;

20 Fig. 2 is a plan view of a timer embodying a preferred form of this invention; and

Fig. 3 is a transverse sectional view, substantially on the line 3-3 of Fig. 2.

In the drawings, particularly Fig. 1, 10 is a source of current supply, such as a battery. 11 represents a manually operated switch for closing the circuit, to an induction coil, which may comprise the usual primary coil 12 and secondary coil 13. 14 represents a resistance coil interposed between the induction coil and the timer 15, which will be more particularly hereinafter described, as provided with a plurality of sets of contacts, which are adapted to open and close the circuit to the ground connection

35 16, which forms a return to the source of current 10. It will be noted that the usual condenser 17 may be arranged to bridge across the gap made by the contacts of the timer when the circuit is broken thereby. A 40 distributor 18, of usual form, may be connected with the secondary coil 13 of the induction coil, as at 19.

Referring particularly to Figs. 2 and 3, 20 represents a casing in which a shaft 21 may be suitably mounted in bearings 22 in a transverse plate 23, mounted on an inwardly extending shoulder or flange 24. 26 indicates an insulating ring of suitable material, such as fiber, on which may be mounted a 50 pair of conductor rings 27 and 27'. These conductor rings may be secured in position, as by the screws 28, the ring 27 being provided with an upwardly extending lug 29, which is adapted to be connected to the terminal 30, which is arranged in the insulating bushing 31, mounted in the casing 20. It will be noted that the terminal 30 is adapted to be secured in position by means of a shoulder 32 formed thereon, and a nut 33, 60 which may be threaded on the member 30.

It will be noted that the induction coil 12, 13, represented in the diagrammatic view, is adapted to be connected, as at 34, to a member 35, which is suitably mounted on terminal 30, and insulated therefrom, and is pro-

vided with an inwardly extending lug 35', to which is electrically connected the resistance coil 14, the other end of which is connected to a housing cap 36, which is in electrical connection with the member 30, and is held in proper position, as by the nut 37. It will be understood that the coil 14 is properly insulated by the spool 38.

The ring 27' is in electrical contact with the conductor plate 27, and is provided with a plurality of lugs 39, in which may be mounted a threaded contact 40, which may be locked in adjusted position, as by the nuts 41. Insulated studs 42, on each of which is pivotally mounted a switch 43, are secured in position as by nuts 44. Each of the switches 43 is provided with a spring 45, which is grounded on the casing 20. Each of the switches is provided with a contact point 46, adapted to be intermittently brought into electrical connection with the contact 40.

It will be noted that the shaft 21 has formed thereon, or suitably secured thereto, a many-sided cam 47, which is provided with eight diametrically opposed ridges 48, a pair of which are adapted to simultaneously raise the insulated abutments 49, which are suitably arranged in the switches 43, as by pins 50.

It will be noted that a conductor 51, which may lead to the condenser 17 has an electrical connection, as at 52, with the terminal 30.

From the above description, the operation of this invention will be understood as follows: Assuming the switch 11 to be closed, current will flow from the source of supply 10 through the primary winding 12, resistance coil 14 to the two lugs 39, and assuming the switches to be closed, the current will be divided between the two, and through the switches 43, passing through their respective springs 45 to the grounded casing 30 and to the battery 10. When the shaft 21 is revolved so that the abutments 49 ride on a pair of ridges 48, the contacts 40 and 46 are broken, thereby building up a charge to be absorbed by the condenser 17, which will be discharged upon the making of the next contact, and thereby energizing the secondary winding 13, from which the current is conducted to the various spark plugs 53 by the distributor 18, which may be driven as desired, from the shaft 21. Of course it is understood that the spark plugs 53 may be grounded in the usual way.

It will be seen from the foregoing description that there has been provided a timer comprising a pair of sets of contacts arranged in parallel, each of which is designed and constructed to carry the entire current flowing through the primary circuit; however, in normal operation, a portion of the current is adapted to flow through each of

the sets of contacts, which, of course, are operated in synchronism.

While I have described and illustrated a preferred embodiment of my invention, it will be understood that various modifications and changes may be made without departing from the spirit and scope of the invention.

Having thus described my invention, what I claim and desire to secure by Letters Patent is:

1. A timer, having a plurality of contacts electrically connected to split the current passing therethrough.
- 15 2. A timer, comprising a plurality of contacts arranged in sets of two or more carrying the same polarity of current, and common means for simultaneously operating the same.
- 20 3. In a timer for ignition systems comprising a single path circuit, the combination of a plurality of intermittently operated contact breakers arranged in parallel in said circuit.
- 25 4. In an ignition system, means for making and breaking a circuit, said means comprising a plurality of contact breakers arranged in parallel.
- 30 5. In an ignition system, means for making and breaking a circuit, said means comprising a plurality of contact breakers, and means for simultaneously operating said contact breakers.
- 35 6. In an ignition system, a timer provided with a plurality of means arranged in parallel for making and breaking the circuit, and a single means for operating said means for making and breaking the circuit.
- 40 7. In an electrical system, the combination with a circuit provided with automatic means for making and breaking said circuit, said automatic means comprising a plurality of switches arranged in parallel.
- 45 8. In an electrical circuit, the combination with a timer therefor, comprising a plurality of spring closed switches arranged in parallel and adapted to be positively and simultaneously opened.
- 50 9. In an ignition system, means for making and breaking the circuit, said means comprising a plurality of contact breakers arranged in parallel and adapted to be operated in synchronism.
- 55 10. In an ignition system, means for making and breaking a circuit, said means comprising a plurality of contact breakers adapted to be operated in synchronism, said breakers being provided with spring actuated means for closing the circuit.
- 60 11. In an ignition system, means for making and breaking a circuit, said means comprising a plurality of switches arranged in parallel, and adapted to be operated in synchronism, said switches being provided with adjustable contacts.

12. In an ignition system, means for making and breaking a circuit comprising a plurality of switches, said switches being provided with adjustable contacts and being so arranged that they are adapted to be operated simultaneously, and are provided with means for causing the switches to open and close their respective contacts in synchronism, independently of their initial adjustment.

13. In an electrical system, a circuit comprising a source of current, a device adapted to be actuated by said current, and means for making and breaking the circuit, comprising a plurality of sets of contacts arranged in parallel.

14. In an electrical system, a circuit comprising a source of current, a device adapted to be actuated by said current, and means for making and breaking the circuit, comprising a plurality of adjustable contacts arranged in parallel.

15. In an electrical system, a circuit comprising a source of current, a device adapted to be actuated by said current, and means for making and breaking the circuit, said means comprising a plurality of adjustable contacts arranged in parallel, adapted to be spring closed and operated in synchronism.

16. In an ignition system, a circuit comprising a source of current supply, an induction coil, and means for making and breaking the circuit, said means comprising a plurality of sets of contacts arranged in parallel.

17. In an ignition system, a circuit comprising a source of current supply, an induction coil, and means for making and breaking the circuit, said means comprising a plurality of sets of contacts arranged in parallel, and a single means for positively operating said sets of contacts.

18. In an ignition system, a circuit comprising a source of current, an induction coil, and means for making and breaking the circuit, said means comprising a plurality of sets of contacts arranged in parallel, and cam means for operating said contacts.

19. In an ignition system, a circuit comprising a source of current, an induction coil, and means for making and breaking a circuit, said means comprising a plurality of sets of contacts arranged in parallel, and cam means adapted to operate said contacts, and means arranged on opposite sides of said cam means, adapted to be operated thereby and to operate said contacts.

20. In an ignition system, a circuit comprising a source of current supply, an induction coil, and means for making and breaking the circuit, said means comprising a plurality of sets of contacts arranged in parallel, and a shaft provided with a cam for operating both of said contacts.

21. In an ignition system, a circuit com-

prising a source of current supply, an induction coil, and means for making and breaking the circuit, said means comprising a plurality of sets of contacts arranged in parallel, 5 a shaft provided with a cam for operating both of said contacts, the respective sets of contacts being provided with means arranged on diametrically opposite sides, and adapted to be operated by said cam and to 10 operate said contacts.

22. In an ignition system, a circuit comprising a source of current, an induction coil, and means for making and breaking the cir-

cuit, said means comprising a plurality of switches arranged in parallel, and provided with adjustable contacts, a shaft arranged between said switches for operating the same, each of said switches being provided with independent means for actuating said switches in opposition to said cam. 15

In testimony whereof I affix my signature in the presence of two witnesses.
